[57] CLAIM

The ornamental design for a burnishing tool, as shown and described.

DESCRIPTION

FIG. 1 is a perspective view of the burnishing tool showing our new design;
FIG. 2 is a top plan view of the design;
FIG. 3 is a side elevational view of the design, with the opposed side elevational view being identical thereto;
and
FIG. 4 is a bottom plan view of the design.

FIG. 1

FIG. 2

FIG. 3

FIG. 4
